CYLINDER AND GUIDE CONSTRUCTION FOR HAMMER-DRILLS.

1,304,442.

Specification of Letters Patent. Patented May 20, 1919.

Application filed September 19, 1918. Serial No. 254,782.

To all whom it may concern:

Be it known that we, LEWIS C. BAYLES and FRED M. SLATER, both citizens of the United States, residing at Easton, in the county of Northampton and State of Pennsylvania, have invented a certain new and useful Improvement in Cylinder and Guide Constructions for Hammer-Drills, of which the following is a specification.

10 This invention relates to hammer and rock drills and in particular to a construction of cylinder and guide member for drills of this type.

15 The objects of the present invention are to provide a hammer drill cylinder and separate guide which may be easily assembled. Further, to provide the guide member which may be securely attached to the cylinder but which is also easily removed when 20 worn considerably in the flanges where they slide in the shell and where they are subject to the greatest strain and wear.

With these and other objects in view this invention consists in the features of construction and operation set forth in the following specification and illustrated in the drawings annexed hereto and forming a part hereof, in which:

Figure 1 shows a longitudinal view of the 30 cylinder and guide, a part being broken away and showing portions of the construction in section.

Fig. 2, a cross sectional view taken on the line 2—2 of Fig. 1; and

35 Fig. 3, a perspective showing the complete construction of cylinder guide and shell.

Referring more particularly to the figures of the drawing, the cylinder is shown made in two sections, but it is obvious that this 40 may be varied and the cylinder made of but one part. In the cylinder selected for illustration 1 refers to the rear section of the cylinder and 2 the front section. These 45 are provided with a bushing 3 extending into both sections, serving to hold both sections in alinement. With the cylinder made of one piece this bushing member 3 would be omitted and the cylinder would be 50 ground and hardened in the usual manner, but with the two-part cylinder construction only the bushing would be hardened and the cylinder parts left unhardened as they have

no wearing parts. Each of the cylinder sections 1 and 2 is provided with a dovetailed portion 4 extending along its lower edge. A guide member 5 extends longitudinally of the cylinder sections 1 and 2 and is provided with portions 5^a engaging the dovetailed portions and is also provided with 60 parallel guiding flanges 6 on either side adapted to engage the guideways 7 of a shell 8 in which the cylinder and guide is adapted to slide. The guide 5 would be made in the same manner with a one-piece cylinder, and in that case the cylinder would be provided with a continuous dovetailed portion 65 extending throughout its length.

Depending from the rear of the rear cylinder portion 1 or from the rear end of the 70 cylinder in the case of a one-piece cylinder, is a lug 9 having a hole 10 bored longitudinally of the cylinder. The guide member 5 is also provided at its rear end with a depending lug 11 having a hole 12 in alinement with the hole 10 provided in the cylinder portion 1. A feed nut 13 having a head 14 passes through the holes 10 and 12 and serves to hold the guide member 5 and rear cylinder portion 1 in alinement and by 80 means of a nut 15 threaded upon the feed nut 13 the parts are held firmly together. The usual feed screw 16 passes through a threaded hole provided in the feed nut 13 by means of which the drill is advanced to the 85 work. The drill is provided also with the usual side rods 19 extending longitudinally of the drill cylinder by means of which the cylinder parts are held firmly together.

From the above it will be seen that a drill 90 has been provided having a cylinder formed of two parts in the form of the invention illustrated, held together in the usual manner by means of side rods and also held in alinement with each other by means of a 95 guide member engaging the cylinder parts throughout their length, the entire construction, that is, the two cylinder parts and the guide member being slidably mounted in a shell member and the rear cylinder 100 member and guide member being held firmly together by means of lugs provided on each whereby they engage and are secured together by means of the feed nut.

It is to be understood that the present 105 showing and description disclose only one

specific embodiment of the present invention and that other forms and modifications are included within the spirit and scope of the invention, as expressed in the appended 5 claims.

What we claim is:

1. In a cylinder and guide construction for hammer drills, a cylinder having portions engaging a guide throughout its length 10 said guide attached to said cylinder at one end whereby said cylinder and guide are held rigidly together.
2. In a cylinder and guide construction for hammer drills, a cylinder comprising a 15 plurality of parts each having portions engaging a guide, said guide attached to one of the parts of the cylinder and holding said cylinder parts and guide in alinement with each other.
3. In a cylinder and guide construction for hammer drills, a cylinder, a guide member engaging said cylinder throughout its length whereby said cylinder and guide are held rigidly together said guide member 20 being provided with flanges adapted to engage guideways provided in a shell in which the drill may be slidably mounted.
4. In a cylinder and guide construction for hammer drills, a cylinder comprising a 25

forward and a rear part, and a guide member 30 engaging both of said parts and fastened to one of said parts holding said cylinder portions in alinement and provided with flanges adapted to engage guideways provided in a shell in which the drill may be 35 slidably mounted.

5. In a cylinder and guide construction for hammer drills, a cylinder, a dovetailed portion on the lower surface of said cylinder, a guide member extending the full 40 length of said cylinder and having portions engaging said cylinder dovetailed portion, said guide member being rigidly attached to the rear portion of the cylinder.

6. In a cylinder and guide construction 45 for hammer drills, a cylinder comprising a front and rear portion in alinement with each other, said portions having dovetailed portions on their lower surfaces, a guide member extending the full length of said 50 cylinder and having portions engaging said cylinder dovetailed portions, said guide being rigidly attached to the rear portion of the cylinder.

In testimony whereof, we have hereunto 55 set our hands.

LEWIS C. BAYLES.
FRED. M. SLATER.
